(57) CLAIM

The ornamental design for a golf practice device, as shown.

DESCRIPTION

FIG. 1 is a perspective view of a golf practice device showing my new design;

FIG. 2 is a top plan view thereof;

FIG. 3 is a bottom plan view thereof;

FIG. 4 is a right side elevational view thereof;

FIG. 5 is a front elevational view thereof; and,

FIG. 6 is a rear elevational view thereof.

The mat is shown in broken lines for illustrative purposes only and forms no part of the claimed design.
